COMBINED LAMP HOLDER AND SUPPORT THEREFOR

Frederick W. Schwartz, Providence, R.I., assignor to Cable Electric Products, Inc., Providence, R.I., a corporation of Rhode Island

Filed Apr. 24, 1964, Ser. No. 79,681

Term of patent 14 years

(Cl. D48—20)

FIG. 1

FIG. 2

FIG. 3

FIG. 4

FIG. 5

FIG. 6

FIG. 1 is a perspective view of a combined lamp holder and support therefor embodying my new design.

FIG. 2 is a front view of the same.

FIG. 3 is a rear view of the same.

FIG. 4 is a top plan view of the same.

FIG. 5 is a side elevation of the same.

FIG. 6 is a bottom plan view of the holder removed from the support.

The dominant features of my design reside in the portions shown in full lines.

I claim:

The ornamental design for a combined lamp holder and support therefor, as shown and described.
